Patented Oct. 30, 1973

228,891

SWIMMING POOL

Richard G. Figueroa, Fremont, Calif., assignor to Concept Design America, Ltd., Fremont, Calif.

Filed July 19, 1971, Ser. No. 164,160

Term of patent 14 years

Int. Cl. D25—99

U.S. Cl. D13—1 G

FIG_1

FIG_2

FIG_3

FIG_4

FIG_5

FIG. 1 is a perspective view of a swimming pool showing my new design;

FIG. 2 is a top plan view thereof;

FIG. 3 is a side elevational view thereof;

FIG. 4 is an end elevational view thereof; and

FIG. 5 is a bottom plan view thereof.

I claim:

The ornamental design for a swimming pool, as shown.
